(57) **CLAIM**

The ornamental design for a thermodynamic converter, as shown and described.

DESCRIPTION

FIG. 1 is a front, top, and left-side perspective view of a thermodynamic converter;

FIG. 2 is a front-elevational view thereof;

FIG. 3 is a rear-elevational view thereof;

FIG. 4 is a left-elevational view thereof;

FIG. 5 is a right-elevational view thereof;

FIG. 6 is a top-plan view thereof; and,

FIG. 7 is a bottom-plan view thereof.

The broken lines in the drawings are for the purpose of illustrating portions of the thermodynamic converter that form no part of the claimed design.

The solid stripe in the drawings is for the purpose of illustrating color contrast between the stripe and the adjacent surfaces.
